UNITED STATES PATENT OFFICE

MICHAEL J. HOGAN, OF CHICAGO, ILLINOIS

INTERCHANGEABLE-CHARACTER-LOCKING DEVICE

Application filed April 18, 1927. Serial No. 184,703.

My invention relates to means for locking interchangeable sign characters in place upon a base and has for its principal object the provision of a device of this character wherein the characters may be readily inserted and removed independently of each other before being locked in place.

Another object of my invention is to provide a device of this character wherein the interchangeable characters may be clamped tightly against each other as well as locked in position.

My invention may be utilized in various forms. One form which is easily constructed and has proven satisfactory is shown in the drawings. However I wish it to be distinctly understood that I do not intend to limit myself to the exact details shown and described but that I intend to avail myself of all such modifications as fall within the scope of the claims.

In the drawings:

Fig. 1 is a plan view of my structure utilized in the sign plate adapted to rest upon a desk or other suitable support;

Fig. 2 is a sectional view taken on the line 2—2 of Fig. 1;

Fig. 3 is a perspective view of one of the sign characters; and

Figs. 4 and 5 are detailed views illustrating the structure of the end character plate.

Referring now in detail to the drawings, the numeral 10 represents a suitable base with which my improved character mounting means may be used. This base clearly consists of a plate-like member which may be of any suitable material such for instance as bronze which is now used in the construction of high grade solid signs of this character.

This base as clearly shown in Fig. 2 is provided with a slot 11 extending longitudinally thereof and in the preferred form this slot is closed on the back side by means of the integral portion 12. The slot 11 is so formed in connection with the portion 12 as to provide a recess as at 13 into which the hook-like portion 14 of the sign character may project.

In constructing these integral characters, I preferably form them in the shape illustrated in Fig. 3, that is, a rectangular plate 15 upon

which the raised character 16 is formed. Upon the back of the plate I provide the rearward projection 17 having a hook-like portion 14 thereon so that a recess is provided along the rear face of the character plate which is adapted to engage the lower edge of the slot 11. As illustrated in Fig. 2, the projection 17 is of considerable less thickness than the slot 11 so that the same may be inserted at any point along said slot and the portion 14 hooked over the lower edge of the slot to temporarily retain the character in place. Thus it will be seen that the characters until locked in place may be moved and interchanged at will to obtain the proper spacing along the slot and by this structure it is not necessary when it is desired to change one character to remove any of the others from the base.

To lock the characters in place I provide the rod 18 which extends from one end of the base through an opening therein to the slot and longitudinally along said slot to the other end thereof, the rod preferably being of such size and so located with respect to the slot that it extends directly along the upper edge of the projection 17 on the characters in place in the slot. By so placing the rod it will be noted that the characters are securely locked in position and cannot, after the rod is inserted, be removed. This provides a very simple and efficient locking means for finally locking the characters in place after they have been properly adjusted and spaced along the slot.

In signs of this character, however, since they are made with a view to imitating as near as possible a solid sign having integral raised characters thereon, it is necessary after the characters are all placed in position, to press them tightly together so as not to leave any cracks therebetween. I accomplish this clamping by a novel means making use of the locking rod in connection with a special end piece 19 fitting into the slot at one end thereof. This end piece as illustrated in Figs. 4 and 5 consists of a flat plate similar to the character plates, but which is provided with the projection 20 on back thereof somewhat larger than the projection 17 it being

made as large as is possible to insert in the slot 11 and is provided like the projection 17 with a hook-like portion 21 adapted to hook over and retain the end piece in position on one edge of the slot.

5 This projection 20 is provided with an opening 22 therethrough which is screw-threaded so as to engage with the screw-threaded end 23 of the rod 18. The end piece 19 is also 10 preferably constructed with a laterally extending flange 23 extending beyond the projection 20 so that upon being drawn away from the end of the slot a short distance necessary to clamp the characters in place it will 15 still cover the end of the slot. The rod 18 is provided with a head thereon as illustrated in Fig. 1 by which the same may be engaged with a screw driver or other suitable tool and turned so as to engage the screw threads in the opening 22 and draw the end plate 19 against the other sign characters and thereby 20 eliminate any cracks or openings between adjacent characters.

From the above description it is thought 25 that the construction and operation of my improved locking and clamping means will be clearly understood and the advantages thereof will be clearly apparent. This structure it will be noted leaves no unsightly projections from the base of the sign and furthermore accomplishes both the locking of the characters in place and the clamping action by means of which the openings between them are eliminated with a single locking member 30 and the special end character construction. By the utilization of this locking means it is also possible to set up the desired characters to establish the proper legend on the sign and properly space them by the insertion or removal of the spacing plates before they are 35 locked in place with a minimum amount of trouble in inserting or removing the characters and then by the insertion of the single element, that is, the rod to permanently 40 lock the character plates in the slots and clamp them together.

Having thus described my invention what I claim and desire to secure by Letters Patent in the United States is:

50 1. A device of the character described comprising a base having a slot therein, a character plate having a projection on the back thereof of less width than said slot whereby it may be readily inserted in said slot, said projection having a recess in one side thereof adapted to receive one edge of said slot and means 55 adjustably mounted on said base for engaging the side of said projection opposite said recess and locking the character plate in 60 position.

2. A device of the character described comprising a base having a slot therein, a plurality of character plates having projections on the back thereof adapted to be inserted in 65 said slot, said projections being recessed to

receive an edge of said slot, and securing means mounted at one end of said slot and engaging the end character plate at the opposite end of said slot said means being adjustable to draw said character plates together.

3. A device of the character described comprising a base having a slot therein, a plurality of character plates having projections on the back thereof insertable in said slot at any point along said slot, and a securing member engaging and locking said projections in said slot said member being adjustably mounted in said base and adapted to engage an end character plate and draw said plates together.

4. A device of the character described comprising a base having a slot therein, a plurality of character plates having projections on the back thereof adapted to be inserted in said slot, and a securing rod rotatably mounted in said base engaging said projections to lock them in said slot and adjustably engaging the projection of an end plate to draw said plates together.

5. A device of the character described comprising a base having a slot therein, a plurality of character plates having projections on the back thereof adapted to be inserted in said slot, and a rod insertable from one end of said base locking said projections in said slot and screw-threadedly engaging a plate at the other end of said slot whereby said character plates may be drawn tightly together.

6. A device of the character described comprising a base having an elongated slot therein, a plurality of character plates having projections on the back thereof insertable through said slot at any point along the length thereof, said projections being recessed to receive an edge of said slot and a securing rod insertable through an opening at one end of said base and extending along the rear of said slot to lock said projections therein, said rod having screw-threaded engagement with a plate at the other end of said base whereby said plates may be clamped together.

In witness whereof, I hereunto subscribe my name this 8th day of February A. D., 1927.

MICHAEL J. HOGAN.
